UNITED STATES PATENT OFFICE.

TRACY GEE, OF CHESTER, MONTANA.

AUTOMATIC CUT-OFF VALVE.

1,286,583.

Specification of Letters Patent.

Patented Dec. 3, 1918.

Application filed March 11, 1918. Serial No. 221,762.

To all whom it may concern:

Be it known that I, TRACY GEE, a citizen of the United States, residing at Chester, in the county of Hill and State of Montana, have invented certain new and useful Improvements in Automatic Cut-Off-Valves, of which the following is a specification, reference being had to the accompanying drawings.

10 This invention relates to certain improvements in automatic cut-off valves and has relation more particularly to a device of this general character especially designed and adapted for use in connection with conduits 15 through which flow gas or other fluid under pressure, and it is an object of the invention to provide a device of this general character having novel and improved means whereby the valve will assume automatically the 20 closed position when the pressure of the flow drops below a predetermined degree.

It is also an object of the invention to provide a novel and improved device of this general character which comprises a pressure 25 chamber interposed within a conduit and which chamber is provided with a diaphragm normally maintained extended under the influence of the pressure within the conduit together with a valve normally 30 maintained in open position under the influence of the controlling member resting upon the diaphragm and which serves to release the valve upon the dropping of the diaphragm so that said valve may assume automatically the closed position.

The invention consists in the details of construction and in the combination and arrangement of the several parts of my improved automatic cut-off valve whereby certain 40 important advantages are attained and the device rendered simpler, less expensive and otherwise more convenient and advantageous for use, as will be hereinafter more fully set forth.

45 The novel features of my invention will hereinafter be definitely claimed.

In order that my invention may be the better understood, I will now proceed to describe the same with reference to the accompanying drawings, wherein:

Figure 1 is a view in side elevation illustrating an automatic cut-off valve constructed in accordance with an embodiment of my invention;

55 Fig. 2 is a longitudinal vertical sectional

view taken through the structure shown in Fig. 1;

Fig. 3 is a view in top plan of my improved valve as herein set forth; and

Fig. 4 is a fragmentary view in perspective of the outer end portion of the stem from which the weighted member is suspended.

As disclosed in the accompanying drawings C denotes a pressure chamber of predetermined configuration and dimension and having its upper face open and provided at its opposite ends with the ports 2 whereby said chamber may be interposed within a conduit or service pipe through which flows a fluid under pressure, such as gas. Disposed over the open or top face of the chamber C is a flexible diaphragm 3 normally maintained expanded or elevated under the influence of the pressure of the fluid within the chamber C. Also overlying the upper or open face of the chamber C is a removable cap 4 having its intermediate portion substantially concavo-convex in order to provide a compartment or chamber A outwardly of the diaphragm 3. The central portion of the cap 4 is provided with an opening affording communication with the chamber or compartment C and extending through said opening is a stem 5 having fixed to its lower or inner end a head 6. The upward movement of the head 6 under the influence of the diaphragm 3 is limited by contact of said head with the marginal portion of the cap 4 defining the opening 5.

The pressure chamber C is provided within a pipe section S and said section rearwardly of the chamber is provided with the upstanding bearings 7 in which is rotatably mounted a rock shaft 8 disposed transversely of said section S. Fixed to the shaft 8 between the bearings 7 is a rock arm 9 which overlies the cap 4 and is hingedly connected with the outer or upper portion of the stem 5 so that upon the rising or dropping of the head 6 the shaft 8 will be correspondingly rocked. Intersecting the section S in advance of the pressure chamber C is a plug valve 10 substantially horizontally disposed and which has a stem 11 extending beyond one side of the section S. Secured to the outer end portion of the stem 11 is a rod 12 extending forwardly of the section A and said rod is of such length as to extend beneath the shaft 8 when in substantially a

horizontal position. The rod 12 at a point below the shaft 8 when the rod is in its substantially horizontal position is provided with a weight 14 and extending forwardly 5 from said weight is an arm 15 terminating in an inwardly directed extension 16 adapted to overlie a beveled end portion 17 of a stem 18 extending outwardly from the end of the shaft 8 and said extension 16 is engaged within a notch *a* produced in said beveled end 17 when the member 6 is elevated under the influence of the diaphragm 3 and the plug valve 10 is in open position. When the pressure within the conduit or service 15 pipe in which the section S is interposed drops below a predetermined degree the diaphragm 3 will fall which results in the dropping of the member 6. As the member 6 drops the shaft 8 is sufficiently rocked as to 20 free the extension 16 from the notch *a* which results in the extension 16 sliding from the stem 18 as assured by the bevel 17 and the weight 14. The weight 14 also assures the desired rotation of the valve 10 to cause the 25 same to assume a closed position so that the flow of gas or other fluid under pressure is prevented until the valve has been returned to open position and it will also be self-evident that the extension 16 can not be operatively engaged with the stem 18 until the 30 pressure of the gas or other fluid within the conduit or service pipe is sufficient to maintain the head 6 in its upper or outward position.

35 From the foregoing description, it is thought to be obvious that an automatic cut-off valve constructed in accordance with my invention is particularly well adapted

for use by reason of the convenience and facility with which it may be assembled and 40 operated and it will also be obvious that my invention is susceptible of some change and modification without departing from the principles and spirit thereof and for this reason I do not wish to be understood as 45 limiting myself to the precise arrangement and formation of the several parts herein shown in carrying out my invention in practice except as hereinafter claimed. 50

I claim:

The combination with a service pipe provided with a pressure chamber, a wall of said chamber having an opening in communication with the atmosphere, a flexible diaphragm intersecting said pressure chamber, a valve arranged within the service pipe and having a rotary stem, a weighted arm carried by the stem of the valve, a member resting upon the diaphragm, a stem carried thereby and extending exteriorly of the pressure chamber through the opening in a wall of said chamber, a rock shaft supported by the pipe and having a beveled end provided with a notch, and an upstanding arm carried by the arm of the stem and engageable within the notch of the rock shaft, the outward movement of the stem being limited by contact of the member with the marginal portion of the chamber defining the opening. 55

In testimony whereof I hereunto affix my signature in the presence of two witnesses.

TRACY GEE.
